Norton A. Mears
by Parker & Carter
Attorneys.

UNITED STATES PATENT OFFICE

NORTON A. MEARS, OF CHICAGO, ILLINOIS, ASSIGNOR TO CHICAGO FORGING & MANUFACTURING COMPANY, OF CHICAGO, ILLINOIS, A CORPORATION OF ILLINOIS

HINGE

Application filed December 5, 1928. Serial No. 323,873.

My invention relates to a hinge and particularly to a hinge which may be used to support two or more adjacently hinged members. One use of my invention is for the hinging of adjacent and overlying cover members. Another object is to provide a hinge in which covers or hinged members may be raised separately or together. Another object is to provide a hinge of the general type disclosed in which all the parts are made of stampings or forgings and in which castings are eliminated. Other objects will appear from time to time in the course of the specification and claims.

15 I illustrate my invention more or less diagrammatically in the accompanying drawings, wherein—

Figure 1 is a side elevation of my hinge with parts in section;

20 Figure 2 is a rear view of the hinge with parts broken away; and

Figure 3 is a section on the line 3—3 of Figure 1.

Like parts are indicated by like symbols throughout the specification and drawings.

A generally indicates any suitable base or abutment upon which the hinge may be employed. A¹ is a hinge base member provided with a square or non-circular aperture A² adapted for example to receive the squared portion A³ of the buttonhead bolt A⁴. The shank A⁵ of the bolt passes through a circular aperture A⁶ in the base A and when the bolt is drawn into position, as by the nut A⁷, the hinge base member A¹ is not only firmly held against the base A, but is held against rotation about a vertical axis. The base A¹ is provided at one end with the upwardly turned ears or lugs A⁸ having the aligned apertures A¹⁰.

B indicates a pivot pin passing through the apertures A¹⁰. It may for example be headed as at B¹ with the opposite end upset as at B² although I do not wish to limit myself to any particular means for or method of holding the pin in place. Mounted for rotation about the pivot B are the hinge members B¹ and B². The member B¹ is indicated as relatively short and as having ears B³ which are curled to form the apertures B⁴ through

which passes the pin B. Note that the ears B³ are positioned exteriorly of the lugs or ears A⁹ of the hinge base A¹. The hinge member B² is provided with a single ear which is curled to form an eyelet B⁵ through which passes the pin B. This eyelet B⁵ is shown as positioned between the lugs or ears A⁹.

Secured to the hinge member B¹, as by the screws C¹ is the lower cover member C. Secured to the hinge member B², as by the screws C² is the upper cover member C³.

The use and operation of my invention are as follows:

When the hinge base member A¹, or a pair of them, when a pair are employed, are placed upon the base A, they may be secured and positioned, as by dropping the carriage bolt or buttonhead bolt A⁸ A⁴ A⁵ into the position in which it is shown in Figure 1. The bolt thus not only holds the hinge against the base A, but also holds it aligned and prevents its rotation about the axis of the bolt. The two hinge members B¹ B² are concentrically pivoted upon the hinge base but are of uneven length. The lower cover member C is secured to one and the upper cover member secured to the other. It will be observed as shown in dotted line position illustrated in Figure 1, that the upper cover C³ may be rotated into vertical position independently of rotation of the cover C. When it is so rotated and positioned its distance from the pivot is sufficient to permit the cover C also to be rotated into vertical position. On the other hand they may both be rotated simultaneously. No matter whether they are rotated simultaneously or not their relation is always the same at the end of the movement of rotation of the two covers.

An additional advantage in my device rests in the fact that it reduces to a minimum the exposed members and tends to give a concealed hinge effect. In doing away with the heavy castings and cross-bar of the present conventional hinge employed for example in toilet seats, I reduce the exposed surface and limit the accumulation of dirt thereon and corrosion thereof. The entire device, the base

and the hinge leaves, including the hinge, is more readily cleaned and kept clean.

I claim:

1. In a hinge for a multiple hinge member, a hinge base and means for securing it and for preventing its rotation about the axis of the securing means, a pivot receiving upward extension from said base, and a plurality of hinge members concentrically pivoted to said extension, said extension including a pair of ears or lugs and a pivot pin extending through said ears, one of said hinge members being provided with bearing portions in engagement with said pin outside of said ears, the other being provided with a bearing portion engaging said pin between said ears.
2. In a hinge and cover assembly, a base member, a plurality of hinge members concentrically mounted thereupon, said hinge members being of unequal length and being adapted to lie, when at either limit of their rotation, in closely adjacent parallel planes, a lower cover member fixed to the shorter of said hinge members and an upper cover member fixed to the longer of said hinge members.
3. In a hinge and cover assembly, a base member, a hinge abutment projecting upwardly therefrom, a plurality of hinged members concentrically mounted upon said hinge abutment, said hinge members being of unequal length, a lower cover member fixed to the shorter of said hinge members and an upper cover member fixed to the longer of said hinge members, said hinge members lying in planes generally perpendicular to the planes of said cover members.
4. In a hinge, a base member, a pivot abutment projecting upwardly therefrom, a plurality of hinge elements concentrically pivoted thereupon, said hinge elements being of unequal length and being adapted, at either limit of their rotation, to lie in closely adjacent parallel planes with the opposed faces of the two hinge members in contact with each other.

Signed at Chicago, county of Cook, and State of Illinois, this 21st day of November, 1928.

NORTON A. MEARS.
